EMILE PRAT, OF PARIS, FRANCE, ASSIGNOR TO SOCIÉTÉ DES CHEMINÉES LOUIS PRAT
À TIRAGE INDUIT, OF PARIS, FRANCE.

DRAFT-PRODUCING DEVICE FOR LOCOMOTIVES.

Application filed April 2, 1920. Serial No. 370,861.

To all whom it may concern:

Be it known that I, EMILE PRAT, citizen of the French Republic, residing at Paris, France, 64 Rue de Miromesnil, have invented certain new and useful Improvement in Draft-Producing Devices for Locomotives, of which the following is a specification.

This invention relates to means for producing draft and is more particularly applicable to the smoke boxes of locomotives but also is capable of being applied to land and marine boilers.

In the case of locomotives, the resistance to the flow of the gases through the nest of tubes is always considerable, and in modern engines, it is advisable to maintain in the smoke box an absolute pressure of about 200 to 300 millimeters water column beneath atmospheric pressure.

For the purpose of producing a considerable fall of pressure below atmospheric pressure, the draft systems in common use, which are dependent upon the expansion of steam, are of low efficiency, the suction-fan system being far more economical; but this latter system cannot be used on locomotives unless it is provided with auxiliary steam devices which enable the draft to be maintained in case the locomotive, and therefore the fan stops.

The object of the present invention is to fulfil these two conditions and to enable one method of operating to be easily changed to the other, while maintaining the highest possible efficiency in the case of both. The apparatus for use in locomotives, comprising a fan through which are passed all the furnace gases to be discharged, is characterized according to the present invention by the employment of a movable throttling device which is capable, on the one hand, of forming, during normal working, an extension from the delivery nozzle of the fan to the chimney, so as to continue the expansion of the furnace gases from the fan outlet, and, on the other hand, on being moved when the auxiliary steam jet is brought into operation, of insuring the expansion of the steam in stages so as to set up an induced draft for the furnace gases through the aspirator formed by the bi-conical portion of the chimney. In the form generally recognized

as the most advantageous, the delivery nozzle of the fan consists of a Venturi tube.

In the accompanying drawing, which shows, by way of example, one method of carrying out the invention, Fig. 1 is a section of the device on a locomotive smoke box under normal running conditions. Fig. 2 is a partial diagrammatic section of the throttling device in position for operating with auxiliary steam jet. Fig. 3 is a detail view, showing a device for supporting and operating the throttling device, this portion having been omitted in Figs. 1 and 2 in order to simplify the drawings. Fig. 4 is an end view of the smoke box, showing the general arrangement of the fans. Fig. 5 is a diagrammatic representation of the form usually assumed by the stream of gases issuing from the nozzle of a fan.

Figure 6 is an enlarged diagrammatic sectional view showing the cooperative relation of the fan, its nozzle and adjacent parts in the same position as in Figure 1, the position of the parts shown in Figure 2 being indicated in dotted lines, and

Figure 7 is an enlarged front elevation of the two steam inlets.

On the smoke box *a* of the locomotive is arranged the intake of the fan *b*, which delivers through a nozzle *c* into the bi-conical chimney *d*. This chimney is preferably horizontal, its rearward portion only being turned up. The movable throttling device *e* is adapted to be moved with reference to the nozzle *c*, by any suitable means, for example by a threaded rod *J*, as shown in Fig. 3 (in order to simplify the drawing, only the end of this rod being shown in Fig. 1). Two annular auxiliary steam jets, *f* and *h*, are also arranged round the nozzle *c*.

In the ordinary course, the throttling device *e* takes up a position behind and in line with the nozzle (Fig. 1), its rearward edge bearing against the chimney *d* so as to shut it off completely from the smoke box. Under these conditions, all the gases to be discharged pass through the fan, which delivers them through the nozzle *c* and the throttling device *e*, in which latter, the diffusion begun in the nozzle is continued.

When the fan is stopped only the steam jet operates and the throttling device is moved into the position shown in Fig. 2.

The steam is able to escape from the ring *f* or from the ring *h*, according as it is exhaust steam coming from the pipe *g*, or live steam coming from the pipe *i*. Moreover, the two 5 may operate at the same time.

On issuing from the ring *f* or *h*, the steam expands in the space comprised between the nozzle *c* and the throttling device *e*, and aspirates a certain quantity of gas, the mixture of gas and steam issuing from the other 10 end of the throttling device under sufficient pressure for the further expansion of this mixture, in the chimney, to set up an inductive effort under the influence of which the 15 remainder of the gas is aspirated.

As the result of these two successive expansions and of the conical (or more usually, bi-conical) shape given to the throttling device *e*, the steam jet is utilized in a 20 very satisfactory manner and the draft produced is comparable to that furnished by the fan.

Thus with a single member such as the 25 throttling device *e*, the working of the locomotive can be maintained whether the fan be working or not.

The bi-conical or Venturi-tube form is adopted for the nozzle *c* because experience has proved that, contrary to the idea previously held, the stream of gases issuing from 30 the delivery nozzle of a fan does not expand immediately, but first of all contracts and then expands very nearly in accordance with the contour *h* indicated in Fig. 5. By 35 adopting this shape of nozzle the loss of efficiency due to eddies, is obviated and the discharge of the gases is facilitated.

For the sake of clearness only the employment 40 of a single fan has been referred to, but it follows, as a matter of course that, in order to facilitate installation in locomotives, and for reasons of symmetry, as well as in order to provide a reserve, it is desirable to provide several groups of fans and 45 chimneys, and more usually two, as shown in Fig. 4.

It should also be noted that this system of 50 draft production is capable of numerous applications in the case of land or marine boilers, because (1) of the tendency to employ boilers with a high rate of evaporation (2) powerful draft is necessary when inferior fuels are used and (3) of the employment 55 of heat regenerators which offer great resistance to the discharge of the smoke.

When the annular steam jet *f* is not in use, the exhaust steam discharged from the

engine cylinders by way of the pipe *g* may be allowed to escape to the atmosphere through a branch pipe *m*; valves *n* and *o* interposed in the pipes *g* and *m* respectively enabling the exhaust steam to be directed either to the ring *f* or into the atmosphere as may be required.

In my co-pending application Serial No. 370860 filed April 2, 1920, I have described an induced draft device by ejector action in which a portion of gases passes inside the fan and the remainder outside the fan, means being provided to control the ratio of 60 the two portions. In my co-pending application Serial No. 370862 filed April 2, 1920, I have further described a draft device in which a fan divided into two parts simultaneously causes the draft of the combustion 70 gases to the chimney in one part of the fan and blows atmospheric air to the furnace grate in the other part. But my present application does not relate to any device of the kind, as it concerns a draft device in which 75 the fan is always traversed, when working, by all of the gases, and in which when the fan is out of work, the gases are carried along by the ejector action of a steam blast.

What I claim is:—

1. In a draft-producing device for locomotives, a chimney comprising a convergent part and a divergent part, a fan adapted to be traversed, when in operation, by the whole of the furnace gases to be discharged, 90 a movable throttling member adapted on the one hand to be moved into close contact with the divergent part of the chimney, thus forming an extension from the delivery nozzle of the fan for the expansion of the gases 95 discharged from the latter, said member being adapted on the other hand to be removed from the chimney wall, means for expanding steam in the space between the delivery nozzle of the fan and the movable member 100 in the latter position, and means for further expanding the steam in the chimney at the outlet of said member.

2. In a draft-producing device for locomotives, a chimney comprising a convergent 105 part and a divergent part, a fan having a discharge nozzle constituted as a Venturi-tube, a movable member adapted to form an extension of said delivery nozzle when the fan is in operation, and to form an expansion passage for steam when the fan is stopped.

In testimony whereof I affix signature,
EMILE PRAT.
